DESIGN FOR A COMB

Theodore Friedman, New York, N. Y.

Application April 20, 1945, Serial No. 119,111

Term of patent 7 years

(Cl. D86—8)

To all whom it may concern:

Be it known that I, Theodore Friedman, a citizen of the United States of America, residing at New York, in the county and State of New York, have invented a new, original, and ornamental Design for a Comb, of which the following is a specification, reference being made to the accompanying drawing, forming a part thereof.

Fig. 1 is a view of a comb embodying my new design and showing one side thereof.

Fig. 2 is a top view thereof.

The other side of the comb not shown is substantially like the side shown.

I claim:

The ornamental design for a comb, substantially as shown and described.

THEODORE FRIEDMAN.
